UNITED STATES PATENT OFFICE.

DAVID EDWARD ALLEN AND DAVID M. FORBESS, OF ARDMORE, OKLAHOMA.

WORK-HOLDER.

1,147,357.

Specification of Letters Patent. Patented July 20, 1915.

Application filed April 3, 1915. Serial No. 19,013.

To all whom it may concern:

Be it known that we, DAVID EDWARD ALLEN and DAVID M. FORBESS, citizens of the United States, residing at Ardmore, in the county of Carter and State of Oklahoma, have invented certain new and useful Improvements in Work-Holders, of which the following is a specification, reference being had to the accompanying drawings.

10 This invention relates to certain improvements in work holders and has relation more particularly to a device of this general character especially designed and adapted for use in connection with tire setting machines; 15 and it is an object of our invention to provide a device of this general character having novel and improved means whereby a wheel may be effectively maintained in applied position and whereby said wheel may 20 be applied to or removed from operative position with convenience and facility.

Furthermore, it is an object of our invention to provide a novel and improved work holder which is carried directly by the machine.

The invention consists in the details of construction and in the combination and arrangement of the several parts of our invention whereby certain important advantages 30 are attained and the device is rendered simpler, less expensive and otherwise more convenient and advantageous for use, all as will be hereinafter more fully set forth.

The novel features of the invention will 35 be carefully defined in the appended claims.

In order that our invention may be the better understood, we will now proceed to describe the same with reference to the accompanying drawings, wherein—

40 Figure 1 is a view, partly in elevation and partly in section, illustrating a work holder constructed in accordance with an embodiment of our invention in applied position; Fig. 2 is a fragmentary elevational view of

45 an elongated member comprised in the present embodiment of our invention; Fig. 3 is a sectional view taken substantially on the line 3—3 of Fig. 1; Fig. 4 is a view in perspective, detached, of the engaging member herein included; and Fig. 5 is a view in perspective, detached, of the straps and their connecting pin as herein set forth.

As disclosed in the accompanying drawings, M denotes a tire setting machine of 50 any ordinary or preferred construction and having projecting upwardly therefrom at

one side thereof the elongated member 1 provided with the longitudinally disposed elongated slot 2 intersected by the transversely aligned openings 3 through which a 60 pin 4 or the like is adapted to be directed, for a purpose which will hereinafter be more fully set forth. Also projecting upwardly from the machine is a yoke 5 in alignment with the member 1 and positioned 65 adjacent the opposite side of the bed of the machine and directed through the upper extremity of said yoke is the removable pin 6 serving as a fulcrum for the lever 7, said lever being provided with a plurality of longitudinally spaced openings 8 whereby the 70 leverage thereof may be adjusted as required.

Disposed through the yoke 5 is an elongated holder bar 9, the upper edge thereof adjacent its opposite extremities being provided 75 with the recesses or sockets 10, the socket at the inner extremity of said bar being adapted to receive the pin 3, hereinbefore referred to, while the second socket is adapted to receive the pin 11 disposed 80 through the lower extremities of the straps 12, the opposite extremities thereof being pivotally engaged through the medium of the pin 14 with the lever 7.

When in applied position, the holder bar 85 9 is adapted to extend above the felly of a wheel and is provided with the freely movable engaging member 15 adapted to be engaged directly with the felly in a manner and for a purpose which is believed to be 90 self-evident. As herein disclosed, said engaging member is substantially U-shape in form and has its stems provided with the elongated slot 16 through which the holder bar 9 is directed and the base 17 of said 95 holder member has swiveled thereto the plate 18 which directly engages the wheel and it will be observed that its swivel connection will serve to prevent any lateral bend of the bar 9.

The upper edge of the holder bar 9 is 100 provided with the rack 22 which may be integral therewith or separable, as the requirements of practice may dictate, and said rack 22 is adapted to be engaged by the pawl 105 19 pivotally engaged with the inner extremity of the lever 7.

In order to hold the straps 12 in an inoperative position, we find it of advantage to provide the lever 7 with a spring catch or 110 clip 20 adapted to be received within an opening 21 produced in one of said straps.

In practice, a wheel is suitably positioned upon the machine M and the holder bar 9 disposed therethrough with one extremity underlying the pin 4 positioned within certain of the alined openings 3 as the necessities of practice may require. The member 15 is then adjusted upon the bar 9 so that the plate 18 may engage the inner face of the wheel felly. The pin 11 carried by the 10 straps 12 is engaged with a socket 10 of the holder bar 9 and the requisite downward pressure is imparted on the bar 9 through the medium of the lever 7 and the bar 9 is effectively held against retrograde movement 15 through the coaction of the pawl 19 carried by the lever 7 with the rack 22 of the bar 9.

From the foregoing description, it is thought to be obvious that a work holder constructed in accordance with our invention 20 is of an extremely simple and comparatively inexpensive nature and is particularly well adapted for use by reason of the convenience and facility with which it may be assembled, and it will also be obvious 25 that our invention is susceptible of some change and modification without material departure from the scope of the appended claims and for this reason we do not wish to be understood as limiting ourselves to the 30 precise arrangement and formation of the several parts herein shown in carrying out our invention in practice.

We claim:

1. In combination with a work support, 35 a member projecting upwardly therefrom and provided with an elongated slot, a pin intersecting said slot, a yoke projecting upwardly from the support and in alinement with the elongated member, a holder bar disposed through the yoke, one extremity of 40 said bar being provided with a socket to engage the pin of the elongated member, an engaging member slidably engaged with the bar, and means carried by the yoke coacting 45 with the bar for imparting pressure thereto.
2. In combination with a work support, 50 a member projecting upwardly therefrom and provided with an elongated slot, a pin intersecting said slot, a yoke projecting upwardly from the support and in alinement

with the elongated member, a holder bar disposed through the yoke, one extremity of said bar being provided with a socket to engage the pin of the elongated member, an engaging member slidably engaged with the 55 bar, a lever pivotally engaged with the yoke, and a member depending from the lever and engageable with the adjacent extremity of the bar.

3. In combination with a work support, 60 a member projecting upwardly therefrom and provided with an elongated slot, a pin intersecting said slot, a yoke projecting upwardly from the support and in alinement with the elongated member, a holder bar 65 disposed through the yoke, one extremity of said bar being provided with a socket to engage the pin of the elongated member, an engaging member slidably engaged with the bar, a lever pivotally engaged with the yoke, 70 a member depending from the lever and engageable with the adjacent extremity of the bar, said member being pivotally engaged with the lever, and means carried by the lever coacting with said member for maintaining the same in inoperative position. 75

4. In combination with a work support, 80 a member projecting upwardly therefrom and provided with an elongated slot, a pin intersecting said slot, a yoke projecting upwardly from the support and in alinement with the elongated member, a holder bar disposed through the yoke, one extremity of 85 said bar being provided with a socket to engage the pin of the elongated member, an engaging member slidably engaged with the bar, a lever pivotally engaged with the yoke, a member depending from the lever and engageable with the adjacent extremity of the bar, the upper edge of the bar being provided with a rack, and a pawl carried by 90 the lever engageable with the rack.

In testimony whereof we hereunto affix our signatures in the presence of two witnesses.

DAVID EDWARD ALLEN.
DAVID M. FORBESS.
